UNITED STATES PATENT OFFICE.

SAMUEL J. CAWLEY, OF BROOKLYN, NEW YORK.

DESIGN FOR AN UMBRELLA-HANDLE.

Specification forming part of Design No. **11,216**, dated June 3, 1879; application filed April 24, 1879.
[Term of patent 3½ years.]

To all whom it may concern:

Be it known that I, SAMUEL J. CAWLEY, of Brooklyn, in the county of Kings and State of New York, have originated a new and useful Design for the Handles of Umbrellas and Parasols, of which the following is a full, clear, and exact description, reference being had to the accompanying drawing, making part of this specification.

My invention is designed to produce a novel and elegant design for the handles of umbrellas, parasols, &c.; and it consists in forming the head of the handle to represent a boat riding the waters; also, for the purpose of giving it a more ornamental and nautical appearance, placing on the side of the boat the letters and words "H. M. S. Pinafore," or some other appropriate and significant character, and adding thereto a rope and attachments, and beneath all placing on the handle an ornamental ring.

The nature of my design is fully represented in the accompanying drawing, in which A represents the body of the handle, preferably of rectangular form. Its surface may be without ornamentation, or carved to give it a more finished appearance.

B represents a boat, beneath which the carving in relief, C, presents the appearance of waves of the ocean. On one side of the boat are carved or otherwise placed the words "H. M. S. Pinafore."

A diversity of ornamentation may be applied to the boat without affecting the essential features of my design.

D represents a cable, rope, or chain, one end of which appears attached to the prow of the

boat and the other to the eyebolt E on the handle.

F is a bead-ring, made of gold, silver, or other suitable metal that will contrast pleasantly with the material of which the handle is made, which is placed beneath the ornamentation forming the head of the handle. The peculiarities of this configuration, conjointly with the ornamentation, form an elegant and graceful article.

What I claim, and desire to secure by Letters Patent, is—

1. The design for an umbrella or parasol handle, consisting of the representation of a boat riding the waters, which forms the head of the handle, substantially as described, and shown in the accompanying drawing.

2. The design for an umbrella or parasol handle, consisting of the representation of a boat riding the waters, having on one side the letters and words "H. M. S. Pinafore," or other suitable characters, and a rope attached to the prow of the boat and to the handle, substantially as described, and as shown in the accompanying drawing.

3. The design for an umbrella or parasol handle, consisting of the representation of a boat riding the waves, with a rope attached to the prow of the boat and to the handle, and a ring placed beneath such ornamentation, substantially as described, and shown in the accompanying drawing.

SAML. J. CAWLEY.
